UNITED STATES PATENT OFFICE.

CHESTER G. VAN BUREN, OF PROVO, UTAH.

BINDER FOR LOOSE-LEAF BOOKS.

No. 890,541.

Specification of Letters Patent.

Patented June 9, 1908.

Application filed August 20, 1907. Serial No. 389,397.

To all whom it may concern:

Be it known that I, CHESTER G. VAN BUREN, a citizen of the United States, and a resident of Provo, in the county of Utah and 5 State of Utah, have invented a new and Improved Binder for Loose - Leaf Books, of which the following is a full, clear, and exact description.

The purpose of this invention is to provide 10 novel details of construction for a book-binding device, that is specially well adapted for clamping the loose leaves of a note book, sketches, clippings of printed matter, or any loose manuscript in leaf form, between suitable 15 cover boards, in a manner which enables a small or large number of leaves to be quickly and securely bound between the cover boards, and also permits the convenient removal of one or more leaves from the book, 20 as may be desired.

The invention consists in the novel construction and combination of parts, as is hereinafter described and defined in the appended claims.

25 Reference is to be had to the accompanying drawings forming a part of this specification, in which similar characters of reference indicate corresponding parts in all the views.

Figure 1 is a perspective view of an open 30 note book showing features of the invention applied thereon; Fig. 2 is an enlarged back edge view of the note book and a rear side view of a novel binding clamp thereon in closed condition; Fig. 3 is a similar view of 35 details to those shown in Fig. 2, but showing said parts in opened adjustment; Fig. 4 is a plan view of the leaf clamp shown in Figs. 2 and 3, seen in direction of the arrow *x* in Fig. 2; and Fig. 5 is a longitudinal sectional 40 view of the back portion of the improved book-binding device, showing a multiple folding clamping member applied for securing a few leaves between the cover boards.

In carrying into effect the features of novelty and utility that constitute the improvement, two flat rigid cover boards 10, 11 are provided, having equal dimensions and 45 rectangular contours. Two corresponding transverse edges *a*, *a'* of the cover boards 10, 11 are hinged together by adjustable means, which permit the covers to be separated or 50 spaced apart at these transverse edges any degree within the capacity of said hinges; the latter, constituting a dominant feature of 55 the invention, consist of novel details constructed and arranged as follows. Two simi-

lar clamping bars 12, 12^a are employed, each comprising a flat metal strip of a suitable length, proportioned to the width of the cover boards 10, 11, and said bars having 60 lapped contact are centrally pivoted together as at *b*, so that their corresponding ends may be spread apart and folded toward each other, as shown in Figs. 2 and 3. Near their ends the opposite edges *c* of each clamping bar 12, 12^a are sloped, so as to gradually reduce the width of said bars from points *c'* thereon to points *c*² near the pivot *b*. Two similar flattened clamping bands 13, 13 are mounted upon the lapped clamping bars 12, 12^a, one 70 each side of the pivot *b*, these bands having such a relative longitudinal width that they will completely fold the bars 12, 12^a upon each other when the bands are slid from the points *c*² toward and near to the points *c'*, this 75 resulting from an engagement of the bands 13 with the sloped edges *c* on the clamping bars.

At opposite ends of the clamping bars 12, 12^a a flange *d* is formed on each one, these similar flanges projecting from the normally 80 lower edges of said ends which are the lower-most ones of the pair of clamping bars. The flanges *d*, *d* are preferably embedded in the transverse edge *a* on the lower cover board 10 and are thereto secured by rivets or other suitable means.

Upon the remaining ends of the clamping bars 12, 12^a, and which respectively trend outward and upward when said bars are diverged, flanges *e*, *e* are formed, which extend 85 above the flanges *d*, *d*. Upon the outer side edge of each flange *e* an ear *e'* is formed, said ears each having a transverse perforation 90 therein.

In the transverse edge *a'* of the normally 95 top cover board 12^a two notches *g* are formed, wherein the flanges *e* and ears *e'* may be introduced. A pintle rod *h*, that is secured in the cover board 11, adjacent to the transverse edge *a'* thereon, is passed through the perforations in the ears *e'* when said rod is inserted 100 through the cover board 11, thus hinging two ends of the lapped and pivoted clamping bars 12, 12^a by their ears *e'* upon the cover board 11.

It will be seen that a number of loose leaves 105 *A*, arranged upon each other and laid upon the cover board 10, may be secured thereupon at its edge *a* by folding the flanges *e*, *e* down upon the rear transverse edges of the leaves *A* and then clamping them thereon by 110 driving the bands 13, 13 toward the ends of the bars 12, 12^a, it being understood that the

flanges e, e had been elevated somewhat by an angular divergence of the ends of the clamping bars, as represented in Fig. 3.

When the sheets A are to be removed from the binder, this may be quickly effected by forcing the bands 13 toward the center of the clamping bars 12, 12^a and then spreading the ends of the latter apart, which will separate the rear ends of the cover boards 10, 11.

10 Provision is made for holding a few sheets of paper or other similar matter in clamped condition between the cover boards 10, 11; to this end a plurality of liner-strips 14 are held connected together and parallel with each other by tapes 14^a. Normally the strips 14 are disposed as shown in Fig. 1, being laid upon the upper cover board 11 and secured thereto by an attachment of the ends of the tapes 14^a, as shown in said figure.

20 If but a few sheets of paper or the like are to be secured at the ends thereof between the cover boards for their protection, said sheets are arranged in proper order on the cover board 10 and a suitable number of the strips 14 are placed one on top of another, until a proper thickness of material is afforded, this tier of strips then being seated over the ends of the lapped sheets of paper, and the clamping device is adjusted for clamping the sheets 30 and strips 14 upon the cover board 10, as has already been fully described.

It is evident that any sheet material within the area of the cover boards 10, 11 may be quickly and securely clamped therebetween 35 at one transverse edge thereof, thereby affording a temporary binding for printed cuttings, sketches, memoranda or other manuscript matter, which is neat, convenient to adjust and that may be produced at moderate cost.

40 Having thus described my invention, I

claim as new and desire to secure by Letters Patent:

1. The combination with two cover boards, of two clamping bars lapped crosswise and pivoted together at their centers, clasping bands on the clamping bars, adapted for closing them toward each other edgewise, and means for connecting the ends of said bars with corresponding ends of the cover boards.

2. The combination with two similar cover boards, of two clamping bars, each flat in the body and having the edges thereof sloped toward the centers of the bars, said bars being lapped together crosswise and pivoted together at their centers, a flange on one end of each bar, projected laterally therefrom and secured on one end of a cover board, perforated ears on the remaining ends of the clamping bars, a pintle rod engaging said ears in their perforations and secured upon the rear end of the other cover board, and two clasping bands mounted on the sloped edges of the clamping bars.

3. In a temporary loose leaf binder of the character described, two cover boards, two crossed and pivoted clamping bars secured by the ends thereof upon one cover board and hinged at the remaining ends on the other cover board, and a series of filling strips that may be placed upon each other and between the cover board at corresponding ends thereof, for pressure on material to be held between the cover boards.

In testimony whereof I have signed my name to this specification in the presence of two subscribing witnesses.

CHESTER G. VAN BUREN.
